COUPLER

Harold K. Smith, Oak Park, Ill., assignor to The Gould Coupler Company, New York, N. Y., a corporation of Maryland

Application April 3, 1931, Serial No. 527,532

3 Claims. (Cl. 213—151)

This invention relates to couplers, and more particularly to automatic railway vehicle couplers so constructed that the knuckle of a connected coupler will not be liable to catch in the throat opening.

The principal object of my invention, generally considered, is to provide an automatic railway vehicle coupler with portions of the knuckle and/or throat opening so bevelled that increased vertical angularity with respect to a connected coupler is permitted, while at the same time the liability of a corner of the knuckle of a connected coupler catching in the throat opening of the coupler head is obviated.

Another object of my invention is to provide an automatic railway vehicle coupler, the knuckle of which has its buffing face reduced, as compared with its pulling face, by the provision of bevelled portions at the upper and lower ends thereof to obviate the knuckle catching in the throat opening of the associated coupler head when associated couplers are subjected to relative vertical angling and/or movement.

A further object of my invention is to so construct the coupler head and associated knuckle comprising an automatic railway vehicle coupler that the catching of the knuckle in the throat opening of an associated or connected coupler is obviated, while at the same time provision is made for increased vertical angling between such connected couplers.

Other objects and advantages of the invention relating to the particular arrangement and construction of the various parts will become apparent as the description proceeds.

Referring to the drawings illustrating my invention, the scope whereof is defined by the appended claims:—

Figure 1 is a fragmentary plan of connected couplers embodying my invention.

Figure 2 is a vertical sectional view on the line 2—2 of Figure 1, looking in the direction of the arrows, and showing the connected couplers after being subjected to relative vertical angling.

Figure 3 is a side elevational view of one of the knuckles detached from its associated head.

Figure 4 is a plan of the knuckle shown in Figure 3.

Figure 5 is a plan of connected couplers corresponding to Figure 1, but showing portions in horizontal section and illustrating a modification.

Figure 6 is a fragmentary front elevation of a coupler head illustrating the embodiment of Figure 5 more in detail.

Figure 7 is a transverse sectional view on the line 7—7 of Figure 6, looking in the direction of the arrows.

Referring to the drawings in detail, like parts being designated by like reference characters, and first considering the embodiment of my invention illustrated in Figures 1 to 4, inclusive, there is shown in Figures 1 and 2 a pair of connected or mated couplers 1 and 2, each involving a head 3 and a knuckle 4 pivotally connected to said head by means of a normally vertical pivot pin 5. Each of the knuckles 4 comprises a tail and lugs portion, as is usual, and the lugs portion has straight or normally vertical pulling faces 6 extending the full height of the knuckle. The buffing faces 7 of the knuckles 4 or lugs portions thereof are normally vertical at their intermediate portions, with their upper and lower portions bevelled or sloped upwardly and rearwardly, as indicated at 8 and 9, whereby the normal buffing faces are of less height than the pulling faces. The bevelled portions 8 and 9 preferably extend from a point 10 near the knuckle pin-hole 11, continuing around the buffing face to near the point of the knuckle, as indicated at 12. The bevelled portions 8 and 9 preferably define acute exterior angles with respect to the buffing face 7, said buffing face, when the coupler is locked, being preferably parallel to the buffing face 16 of the head, and the width of the horizontal projection of the bevelled portions preferably being less than the normal clearance provided between the buffing face 16 of the head and 7 of a mated knuckle, as shown most clearly in Figure 1.

Figure 2 shows how this bevelling acts to prevent the knuckle of one coupler hanging up on the other when the associated railway vehicles are taken over track of vertical curvature, or when one vehicle is moved and angled vertically with respect to the other. The beveling 8 and 9, it will be seen, slightly increases the permissible vertical angling between the couplers, while at the same time it prevents the upper or lower edge of the buffing face of the knuckle 4 from catching in the throat opening 13 of an associated head, or catching or hanging on the upper buffing wall 14, or the lower buffing wall 15 defining the throat opening 13 when the associated coupler moves downwardly or upwardly, as the case may be, and angles with respect thereto. Figure 2 shows the coupler 1 raised, as compared with the coupler 2, and angled downwardly or clockwise about its connection with said coupler 2, illustrating how the bevel

9 prevents the knuckle 4 from catching on the lower buffering wall 15 forming part of the buffering face 16 of the head 3 of the coupler 2.

At the present time, 9" knuckles are generally used, but, under certain conditions, 11" knuckles are used. It is contemplated to eventually make the 11" knuckles standard in order to reduce the number of slip-overs, that is, one knuckle slipping over the knuckle of a connected coupler under heavy pull and permitting the train to part, especially when one coupler is higher than the other, due to vertical curvature or irregularity in the track. The 11" knuckle would reduce the possible vertical angularity of the couplers and would, therefore, not be satisfactory without a bevel such as previously described. The angle of beveling, as shown most clearly in Figure 2, preferably corresponds approximately with the permissible vertical angling between connected couplers, being desirably slightly greater, to thereby avoid engagement between the upper or lower edges of the bevelled portions 8 and 9 and the head of the connected coupler. It will also be understood that when displaced to a greater extent vertically so as to permit greater angular displacement, the corner of the knuckle would then be liable to catch in the throat opening unless bevelled as previously described. By beveling the buffering faces of the knuckle only, the afore-mentioned difficulties are obviated, and at the same time by making the pulling faces straight or without a bevel, slip-overs are less apt to take place.

Owing to the large increase in hump yards throughout the country, and dumping machines which result in vertical angling of the couplers, and owing to the fact that integral striking castings are generally provided which materially limit the vertical clearance between coupler shank and top wall of the casting, and also to the integrality of the casting which minimizes springing of the parts, face damage to couplers is becoming more prevalent, and cracked knuckles are being constantly replaced, the cracking of the knuckles and damage to the faces being due to the cramping action between the coupler knuckles when the couplers are subjected to vertical angling. All these conditions have brought about the necessity of permitting vertical angling of the couplers to a greater extent than now permissible, and at the same time obtaining the greater benefits of the knuckles of increased vertical height to prevent slip-overs between light and loaded cars or cars under conditions in which the couplers are out of alignment during train operation.

Referring now to the embodiment of my invention illustrated in Figures 5, 6 and 7, a construction is there disclosed in which the throat opening 13^a is defined by buffering walls 14^a and 15^a of the coupler head 3^a having bevelled edges around said throat opening 13^a, as indicated at 17 and 18. This beveling avoids the danger of the knuckle of an associated coupler catching in the throat opening in a similar way as when the knuckle is bevelled, such a knuckle 4^a being diagrammatically indicated in Figure 7 in angled position, showing how the beveling 18 tends to obviate catching on the lower buffering wall 15^a comprising part of the buffering face 16^a of the coupler head 3^a.

The beveling of the throat opening may be alternative or additional to the beveling of the knuckle, as described in connection with the previous embodiment. Said beveling may also

be applied to a coupler head in which the buffering face is reinforced, as shown most clearly in Figure 7, the reinforced face being designated by the full line 16^a and the position of the standard or normal face being designated by the dot-dash line 16^b. It will be seen that by beveling the portions of the reinforced face 16^a adjacent the throat opening to a position corresponding with the normal position of such buffering face, a construction is effected with the advantages of the reinforced face, while avoiding the disadvantages of such reinforced face, which would minimize vertical angling between associated couplers, as well as decreasing the danger of the knuckle of an associated coupler catching in the throat opening. It will also be understood that such beveling of the throat opening may, if desired, be applied to a coupler head in which the buffering face is normally disposed, or unprovided with reinforcement such as shown in Figure 7.

From the foregoing, it will be seen that I have devised an improved coupler which minimizes the danger of catching between a knuckle and the buffering faces of an associated coupler head in the throat opening of such head, while at the same time not sacrificing any of the advantages of the usual coupler construction. Although the knuckle and/or head has been shown as chamfered or beveled straight and forming an acute exterior angle with the associated buffering face greater than, but approximating, the permitted angularity between the couplers, I do not wish to be limited to this showing as, if desired, the buffering face or faces may be formed with a chamfer or bevel not straight and on a different angle, but of such a character as to produce the desired effect.

Although preferred embodiments of my invention have been disclosed, it will be understood that modifications may be made within the spirit and scope of the appended claims.

I claim:—

1. A railway vehicle coupler having a head member and a knuckle member pivotally mounted thereon, said knuckle member being formed with a lugs portion and a tail, said lugs portion of the knuckle member having a buffering face normally extending vertically and said head member being formed with a buffering face normally extending vertically, the buffering face of said head member being formed with an opening for receiving the tail of the knuckle member, and beveled faces at top and bottom of said opening each of which forms an acute exterior angle with said buffering face of the head.

2. A railway vehicle coupler comprising head and knuckle members movably connected, said head member having a portion providing a buffering face and formed with an opening for receiving a portion of the knuckle member, the buffering face portions of said head member, immediately above and below said opening, being inclined with respect to said buffering face and forming acute exterior angles therewith.

3. A railway vehicle coupler comprising head and knuckle members movably connected, said head member having a portion providing a buffering face and formed with an opening for receiving a portion of the knuckle member, the buffering face portion of said head member, vertically adjacent said opening, being inclined with respect to said buffering face and forming an acute exterior angle therewith.
